UNITED STATES PATENT OFFICE.

FRANK C. MEICHESNER, OF BOSTON, MASSACHUSETTS.

PELORUS.

1,367,918.

Specification of Letters Patent.

Patented Feb. 8, 1921.

Application filed October 27, 1919. Serial No. 333,497.

To all whom it may concern:

Be it known that I, FRANK C. MEICHESNER, residing at Boston, in the county of Suffolk and State of Massachusetts, formerly a subject of the Emperor of Germany, who have now taken out my first papers as a citizen of the United States, have invented a new and useful Improvement in Peloruses, of which the following is a specification.

10 My invention relates to a pelorus having advantages over other peloruses now known to me in that provision is made such that the gimbal rings on which the operative parts are mounted are supported above the 15 housing so that the dial and parts mounted above it may swing to a greater angle to normal than is customary in instruments of this kind, thus vastly increasing the utility of the instrument. My invention also relates to improvements in certain details of 20 construction as will be explained below.

My invention will be understood by reference to the drawings, in which—

25 Figure 1 is an elevation of a pelorus embodying my invention, its cover being in section;

30 Fig. 2 being a vertical section therethrough on an enlarged scale, the cover being removed and the alidade being in operative position.

Fig. 3 is a plan.

Fig. 4 is a section on line 4—4 of Fig. 2, and

Fig. 5 a section on line 5—5 of Fig. 3.

35 A is a pier which may be of any desired form and which preferably contains an electric switch indicated at A¹ in the circuit a carrying the electric light. B is the housing formed in the shape of a deep cup on which 40 the pelorus proper is mounted. The housing carries at its bottom a flanged ring B¹ which rests upon a cap A² forming the top of the pier. The flange of the ring B¹ is slotted down one side, the edges of the slot being 45 provided with lugs b by means of which and the thumb screw G¹ the housing is clamped to the top of the pier. A ring C surrounds the upper part of the housing B near its top and is suitably attached thereto. This ring 50 has a flange c projecting upwardly and forming an upper edge for the housing B. At two opposite points it is higher than at the points 90° therefrom, and these higher points carry thickened portions or ribs c¹, 55 which form bearings for the pins d of the outer gimbal ring D. The inner gimbal ring

E comprises a downwardly-projecting flange e having similar ribs e¹ which are secured to the outer gimbal ring by screw pins e² and which has on its inner edge a shoulder e³ 60 supporting the glass plate F².

F is a dial having perforations f which may be in the form of letters, figures or other indications of the points of the compass.

The dial F is located under the glass plate 65 F² and has a downwardly-projecting hub or boss F¹. In this hub is mounted the lower end of a stud H threaded at its bottom and held in place by a nut h. The upper end of this stud H is also threaded as at h¹ and 70 it is enlarged as at h² to form a bearing which rests on the dial F. A washer g surrounding the stud H rests on the dial F. It is thicker near its center than at its periphery and forms a bearing for an enlarged 75 portion h³ of the stud H. It is recessed on its upper side to receive a spring washer h⁴ and a spring sleeve g¹ within which is a nesting g² keyed to the stud H as at h². Thus the nesting and stud will turn together 80 and independently of the sleeve unless the sleeve is clamped thereto as described below. On the washer g and the inner edge of the inner gimbal ring E (which is recessed for the purpose) is cemented a glass disk Q, and 85 on this disk is a washer also cemented thereto, which serves to support the parts above it and surrounds the spring sleeve g¹, these two washers serving as a clamp for the center of the glass disk and also as a gimbal 90 box within which the stud H may be turned. To the sleeve g¹ is attached, to move therewith, the base plate L of the alidade, which comprises a central portion which surrounds the sleeve and bushing, and projecting arms 95 l which are connected at their outer ends by a crossbar l¹ carrying an upwardly-projecting lug l². It also carries a projection l³ near the sleeve, which member has a threaded opening registering with the spring member j of the sleeve. This spring member j of the sleeve as shown comprises a curved finger which may be pressed against the bushing g² to clamp the plate thereto, and thus clamp the alidade. The alidade is of 100 usual construction so far as the arrangement of its sighting members is concerned. It comprises a central portion m from which project oppositely two forked pieces M, M¹, to which the sighting members m¹, m² are 110 hinged, the member m² carrying a hinged member m³, a level m⁴ and a pointer m⁵.

On its under side it has a recess to fit over the projection l^3 on the base plate L and of sufficient size to allow the alidade to move concentrically with reference to the plate. 5 The outer end of M comprises two upright arms m^7 , m^8 between which lies the lug l^2 so that the base plate L and alidade must move together. Through an opening in the lug l^2 and the threaded opening through the 10 projection l^3 passes a rod l^4 having a thumb head l^5 at one end, its threaded end being adapted to engage the finger j and clamp it against the bushing g^1 .

The lug l^2 lies between, and is narrower 15 than, the opening between the arms m^7 and m^8 . Through a threaded opening in the arm m^7 passes the screw m^9 . The arm m^8 carries a socket member m^{10} within which is a spring m^{11} and a pin m^{12} , and the lug 20 l^2 lies between the screw m^9 and the spring-controlled pin m^{12} , and by turning the screw m^9 the alidade may be adjusted slightly about its center, to get a proper sight, against the resistance of the spring head.

25 These parts are held in place on the stud H by a nut J^1 and cap nut J^2 which carries a set screw j^2 to clamp it. To adjust the parts so far described, the dial F is first adjusted. This is accomplished by loosening 30 the nut J^1 so that it will not clamp the alidade, and turning the stud H by the cap nut J^2 until the proper adjustment is secured. The nut J^1 is then screwed down to clamp the lower surface of the sleeve g^1 against 35 the spring washer h^4 and so clamp the dial, but leaving the alidade so that it may be turned in either direction to get a general adjustment of the sights after which the fine adjustment of the sights is secured by the 40 screw m^9 , the alidade being then locked by the screw l^5 acting on the spring finger j .

From the inner gimbal ring project downward four arms K to the bottom ends of which is attached a weighted ring K^1 , which 45 supports from its top springs k which engage and hold in place a support K^2 for a lamp socket carrying a lamp K^3 , this latter construction being such that the weight K not only maintains the parts carried by the 50 gimbal construction normally in horizontal position, but maintains the light in substantially fixed relation to the dial so that it will always show through the openings in the dial and glass plate with the same intensity.

55 From the outer edge of the inner gimbal ring E and attached thereto projects downward a hood E^1 large enough in diameter to allow the gimbals to swing freely, and 60 over the top of the alidade when closed is a cover E^2 which is held in place by fingers E^3 which spring over the bottom of the cover.

65 By supporting the gimbal ring mechanism say an inch or so above the upper edge of the housing, it will swing freely and through

a greater angle without engagement with the housing than if located within the housing or on a level therewith. Thus the device as a whole can be made more compact, the dial, etc. being of nearly the diameter of the 70 interior of the housing, while the locking screw will not engage the housing as the gimbals swing.

The pelorus is watertight, the hood E^1 serving to shed water without in any way interfering with the swing or rotating of the 75 parts.

I prefer to provide the upper edge of the ring E with index marks α a known distance apart, two only of which 180° apart 80 are shown, to act as guides in setting up the pelorus aboard ship, the pelorus being set so that either set of marks point either exactly in the direction of the bow and stern 85 or in a line parallel to a line joining bow and stern.

The lamp K^3 is connected by wires α with binding posts a^2 (one only being shown) set into sockets a^3 in the top of the base A, and are insulated therefrom, these sockets being 90 connected by the wires α with the switch A^1 so that the circuit through the light may be closed at will. Pins P are also provided in the bottom of the housing to set into corresponding sockets in the top of the base to 95 keep the housing from turning when once set. A pin E^4 may be provided to lock the gimbals. The glass plate F^2 serves as a support for the dial and its stud H.

I do not mean to confine myself to the 100 details of construction shown in the drawings and above described, as it will be understood by those skilled in the art that my invention may be otherwise embodied.

What I claim as my invention is:—

1. A device of the kind described comprising a housing, a gimbal mechanism having a dial and an alidade mounted thereon, and means for supporting said gimbal mechanism above said housing whereby said gimbal mechanism and the parts mounted thereon may be oscillated without engagement with the edge of said housing and a hood forming part of said gimbal mechanism and hanging therefrom outside said 110 housing.

2. A device of the kind described comprising a housing, supports mounted on two opposing sides thereof and projecting above the edge of the housing, a gimbal mechanism 120 mounted on said supports near the top thereof and having a greater diameter than the housing, and a dial and alidade mounted on said gimbal mechanism whereby said gimbal mechanism and the parts supported 125 thereon may swing freely without engagement with said housing.

3. In a pelorus, a base plate, an alidade mounted thereon, said base plate carrying an upright projection at one end and said 130

alidade carrying at one end two upwardly-projecting arms, said base plate projection lying between said arms and being adapted to move one arm to the other, and means for moving it.

4. In a pelorus, a base plate, an alidade mounted thereon, said base plate carrying an upright projection at one end and said alidade carrying at one end two upwardly-projecting arms, said base plate projection lying between said arms and being adapted to move from one arm to the other, means for moving it, and means for locking it in any desired position.
- 10 5. In a pelorus, a stud, an alidade, a base plate therefor having a collar located to turn on said stud, said collar having a finger, and means to engage said finger and clamp said base plate to said stud.
- 15 6. In a pelorus, a stud, an alidade, a base

plate having a collar located to turn on said stud, said collar having a finger adapted to clamp said base plate to said stud, means for so clamping it, an alidade mounted on said base plate and having a motion with 25 relation thereto and a motion therewith around said stud, and means for adjusting said alidade with relation to said base plate.

7. In a pelorous, a housing, a gimbal mechanism supported thereon, a transparent 30 dial mounted on said gimbal mechanism, and an alidade also mounted thereon, said dial and said alidade being free to be rotated, means for clamping them in any desired position, a weight suspended from said gimbal 35 mechanism and means on said weight for supporting a light whereby said light will be located in said housing and said dial and alidade may be read.

FRANK C. MEICHESNER.
